UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

INSOLE-BLANK AND METHOD OF PREPARING IT.

1,212,490.

Specification of Letters Patent. Patented Jan. 16, 1917.

Application filed August 7, 1914. Serial No. 855,591.

To all whom it may concern:

Be it known that I, ALBERT E. JOHNSON, a citizen of the United States, residing at Beverly, in the county of Essex and State 5 of Massachusetts, have invented certain new and useful Improvements in Insole-Blanks and Methods of Preparing Them; and I do hereby declare the following to be a full, clear, and exact description of the invention, 10 such as will enable others skilled in the art to which it appertains to make and use the same.

This invention relates to the preparation of insole blanks, and more particularly to 15 such blanks used in the manufacture of welted boots and shoes.

Boots and shoes as commercially manufactured employ a shaped counter or stiffening piece of sole leather, shaved thin at the 20 edge, in the back part of the shoe, within the upper, to support the outer leather and prevent the shoe from "running over." In welt shoes the size and length of the counter is such that, when lasted in, it extends forward under the rear ends of the welt. Ordinarily the welt extends rearwardly to about the breast line of the insole and the counter extends forwardly a considerable 25 distance beyond this line, resulting in these two parts overlapping each other from five-eighths of an inch to an inch and a quarter. Welt insoles for high grade shoes, known as "regulars" or "solids" from the fact that 30 no reinforcing material is used in making them, are fitted with an edge slit forming a lip and feather, or with an outer shoulder in women's work, and with a parallel slit within the edge slit forming a channel and channel flap. The portion between these 35 two slits is the "between-substance." Sometimes the flap inside the between-substance is omitted. These parts form the rib to which the upper and welt are stitched in the inseaming operation. Heretofore these 40 two slits, of whatever form they may be, have been started and terminated at about the breast line of the insole and after the insole has been fitted in this manner the lip, in men's work, is turned and laid over upon the between-substance substantially as shown 45 in Fig. 28 of my prior Patent No. 638,394 dated December 5, 1899. When the outsole is laid, before the heel is secured to the shoe, there is, at each side of the heel seat 50 beneath the outsole for a short distance back

of the breast line of the heel a substantial protuberance formed by the overlying layers of the lip, counter and welt. This is disadvantageous in that it prevents nailing the heel on level and mars the appearance of 55 the finished shoe at the shank for reasons which will presently be explained.

The object of the present invention is to 60 prepare, or fit, insole blanks for use in boots and shoes in such a manner that, whatever 65 the parts used in the construction of the shoe may be, the heel will be seated level and the shank will not be disfigured. As a 70 result of the use of this novel insole the appearance of the shank portions of the 75 cheaper grades of shoes can be made as neat and attractive as the shanks of high grade 80 shoes at present, on which much more care is bestowed in the making.

In accordance with this object, the invention 85 contemplates fitting the insole blank in a manner to permit the counter and upper to be lasted in, and the welt end to be brought down, to substantially the level of the heel seat. The preferred manner of fitting 90 the insole blank to attain this result is to entirely remove that portion of the lip which otherwise would be below the ends of the counter and welt, leaving at this point only the outside shoulder of the between- 95 substance as a striking surface or abutment for the needle of the welter in performing the inseam sewing operation. A recess is thus provided at each side of the shank which enables a closer lasting down of the 100 counter and upper, and provides for the reception of the beveled or "butted" welt end. An especial advantage of this recess is that it permits the welt to be drawn in and lie straight along the shank. If not well lasted 105 in, the inseam at this point is necessarily sewed full with the resulting difficulty that when the outsole is trimmed the outseam is cut into by the trimming knife. As a result of this novel fitting a level heel seat is obtained and the lines of the welt and outsole 110 at the shank are straight, two essentials in the manufacture of fine appearing shoes.

The particular steps employed in preparing the insole blank and their preferred sequence, as well as the preferred form of the insole blank, will be hereafter explained in connection with the accompanying drawings, in which,

Figure 1 is a plan of an all leather insole 210

blank for welt shoes; Fig. 2 is a side elevation of the insole blank shown in Fig. 1; and Fig. 3 is a transverse section on the line 3—3 of Fig. 1.

- 5 Referring to the drawings, 1 is an insole blank prepared in accordance with the present invention having on its flesh side the lip 2 and feather 3 produced by the edge slit 4, and the flap 5 and channel beneath it produced by the face slit 6. The between-substance is indicated by the space between the parallel dotted lines 7 in Fig. 1, and varies in width from $\frac{1}{8}$ " in women's work to $\frac{3}{16}$ " in men's work. The face slit 6 starts and 10 terminates at substantially the breast line of the insole, as shown best by Fig. 1, but the edge slit 5 starts and terminates some distance in advance of the breast line as indicated at 8.
- 20 The shaded portions at each side of the heel seat 9 (Fig. 1) represent recesses 10 of a depth substantially equal to the thickness of the lip 2, of a width substantially equal to the width of the feather, and extending 25 longitudinally substantially from the insole breast line, at their rear ends to a point opposite the ends of the counter at their forward ends. Thus there is no lip 2 along the outer edge of the between-substance 7 where 30 the recesses 10 are formed, the striking surface for the needle of the inseam sewing machine being provided for by the shoulders 11 which form the inner walls of the recesses. The recesses 10, as indicated above, are so 35 disposed that in the lasting operation the forward portions of the sides of the counter will be received therein and after the inseaming operation the skived ends of the welt will lay thereover. Remembering that 40 there is no portion of the lip set over upon the between-substance adjacent the recesses it will be understood that these recesses effectually take care of the ends of the counter and welt in the manner described gaining 45 all of the advantages in the making and appearance of the shoe heretofore explained as being desirable.

In preparing the insole blank it is immaterial when the recesses 10 are formed but 50 for reasons hereinafter set forth it is preferred to cut the recesses before producing the stitch receiving rib. With some insole channeling machines difficulty is experienced in "cutting-in" at the breast line with 55 the edge knife which produces the lip 2 and feather 3. It has been the practice for many years to run in and out across the heel seat, as is illustrated in Fig. 2 of patent to Webb No. 1,060,300, April 29, 1913, but such 60 practice cuts into and weakens the heel seat which should be kept as strong as possible for the reception of the heel nails. It is therefore, preferable to cut the recesses 10 in the unchannelled insole blank so that the 65 edge knife of the channeling machine may,

at the beginning of the channeling operation, rest in the recess at the starting side of the blank and commence the slit 4 by cutting in at the base of the shoulder 8 in the plane of the bottom of the recess. In finishing 70 the channeling operation at the opposite side of the insole the edge knife may readily be raised from its operating position when it reaches a position in the recess. It will be obvious, however, to those skilled in the art 75 that the recesses 10 may be formed by cutting away the lip 2 for the desired distance after this lip has been formed in the channeling operation. The essential feature, it will be observed, is the production in the 80 finished sole of provision for receiving the ends of the counter and welt to gain the advantages already adverted to irrespective of the order in which the steps are taken.

While the description of the invention 85 for ease of explanation, has been directed especially to its application to a particularly described type of insole, it will be obvious to those skilled in the art that its utility is not confined to that type of insole 90 alone.

Having thus described the novel insole blank of the present invention and the method by which it may be prepared, what 95 is claimed as new, is:—

1. An insole blank for boots and shoes having an elongated unlined recess in its flesh side located at each side of the shank adjacent the breast line and having a length less than the length of the shank to receive 100 the ends of the counter and welt.
2. An insole blank for boots and shoes having an unlined recess in its flesh side located at each side of the shank, the rear end of the recess being located adjacent the 105 breast line, and the forward end lying wholly within the shank portion to receive the ends of the counter and welt, and of a width substantially equal to the width of the desired feather at this point. 110

3. An insole blank for boots and shoes having a stitch receiving rib comprising a between-substance extending throughout the shank and forepart, a channel along the entire inner edge of the between-substance, a 115 lip along the greater portion of the outer edge of the between-substance, and a shoulder along the remaining portion of the outer edge of the between-substance in the rear of the lip at the two shank ends thereof. 120

4. An insole blank for boots and shoes having a continuous channel extending throughout the shank and forepart, and a parallel, continuous lip outside the channel but of less length than the channel. 125

5. The method of preparing insole blanks for boots and shoes which comprises channeling an insole to form a marginal lip and raising the lip to provide a stitch receiving rib and in cutting an elongated portion cor- 130

responding to the lip from substantially the breast line of the insole forward on both sides of the shank to form a recess for the reception of the ends of the counter and welt.

6. The method of preparing insole blanks for boots and shoes which consists in cutting an elongated recess in its flesh side located at each side of the shank in position to receive the ends of the counter and welt, and

in thereafter cutting a channel extending around the forepart from substantially the rear end of one recess to substantially the rear end of the other recess, and a lip extending from the forward end of one recess to the forward end of the other recess.

ALBERT E. JOHNSON.
